DRUM

Edmund Hamel, Siegmar-Schonau, near Chemnitz, Germany

Application October 25, 1937, Serial No. 170,989
In Germany November 25, 1936

1 Claim. (Cl. 242—43)

This invention relates to drums in cross winding frames.

One object of the invention is to prevent the thread from jumping out of the groove in which it is guided on the outside of cam drums for producing cross wound bobbins or cheeses. This tendency to jump is due to the difference in thread tension which is for instance not the same at the drum reversing points and in the center between these points.

For this purpose the groove in the surface of the drum has the form of a spiral channel which after one rotation of the drum returns to its starting point and, within range of the reversing points, has a depth sufficient to prevent the thread guided on the bottom of the channel from being raised up to the surface of the drum. In the center between the reversing points the groove is, on the other hand, so deep that the thread portion guided therein has always the same length at any position of the drum.

By way of example, the invention is illustrated in the accompanying drawing, in which Figure 1 shows a drum having a closed guide groove, one of the reversing stations being shown in section; and

Fig. 2 is a section on the line 2—2, of Fig. 1, showing the differences in the depth of the thread guiding channel;

Fig. 3 is a section on the line 3—3, of Fig. 2. Referring to the drawing, the guide drum comprises a cylindrical body 1 having a closed guide groove 2 which has a relatively low depth

within range of the reversing stations at 2'. The depth increases, however, toward the center in the direction 2'' at which point it is several times as great as at the reversing points. This difference in depth serves for keeping the thread portion guided in the channel always at the same length, so that the speed of the thread remains constant.

The catch 3 facilitates the insertion of the thread during rotation of the drum which may be made of any suitable material. It may further be made in one piece or composed of two members to suit requirements.

I claim:

A one piece drum for cross winding frames having a groove on its outside, said groove having a closed bottom and lateral walls united with the bottom, said bottom being substantially oval shaped in cross section, said groove forming a channel which returns to its starting point after a rotation of the drum, said groove also having its minimum depth at the thread reversing points and preventing the thread guided on the bottom of the channel from being raised by thread tension to the surface of the drum, and increasing in depth toward the center between the reversing points to maintain uniform length of the thread portion guided in the groove at any position of the drum, said increase in depth of the groove being gradual from the thread reversing point to the center of the oval.

EDMUND HAMEL.
